(57) CLAIM

The ornamental design for an incense burner and palo santo stick and sage bundle holder set, as shown and described.

DESCRIPTION

FIG. 1 is a top perspective view of an incense burner and palo santo stick and sage bundle holder set showing my new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof; and,

FIG. 9 is a perspective view of the incense burner and palo santo stick and sage bundle holder set in another configuration of use.

The broken lines in the drawings depict portions of the incense burner and palo santo stick and sage bundle holder set that form no part of the claimed design.

1 Claim, 9 Drawing Sheets
